UNITED STATES PATENT OFFICE.

FREDERICK THOMAS ATKINSON, OF CINCINNATI, OHIO.

PROCESS OF STAINING WOOD.

1,403,536.

Specification of Letters Patent. Patented Jan. 17, 1922.

Application filed August 14, 1919. Serial No. 317,609.

To all whom it may concern:

Be it known that I, FREDERICK THOMAS ATKINSON, a citizen of the United States, residing in Cincinnati, in the county of Hamilton and State of Ohio, have invented a new and useful Process of Staining Wood, of which the following is a specification.

My invention relates to the process of staining or coloring woods in imitation of other woods, and of staining or coloring sap wood or alburnum to correspond in color with the heart wood or duramen, and it has for its object the saving of waste, and a more natural, thorough, expeditious and cheaper process of staining wood.

In the drawing:

Fig. 1 represents a perspective inside elevation of a container, with one of the walls of the container removed, and having the wood arranged therein in a preferred position, for performing my improved process.

Fig. 2 is a perspective view of one of the pieces of wood, showing one end thereof in cross-section, and the other end thereof broken away.

There exists a necessity for such a process because nearly all woods possess sap-wood of a different color from that of the heart wood and in some woods, such as American black walnut, wild cherry, butternut, birch, etc., the difference between the color of the heart and the sap wood is so marked as to cause the sap wood to lose its value as a wood peculiar to its kind. Sap in most of the woods is considered a defect for the reason that its color differs from that of the heart wood, rather than for any other reason, excepting, perhaps, its inferior durability when exposed to the inclemency of the weather.

In order to utilize the sap wood in furniture, interior finish, etc., it is necessary to stain it to correspond in color with the heart wood. If it is not stained, then it must be eliminated and becomes waste.

For most practical purposes, the sap wood is just as valuable as the heart wood, but is not desirable because of its color. In order to eliminate the sap, a certain amount of the heart wood is also wasted. To stain this sap to correspond with the color of the heart wood means an enormous saving of

the sap as well as the heart wood, in addition to the enhancement of the value of the sap wood.

The duramen or heart wood of the various species of timber contains a coloring matter peculiar to its kind and when the wood is put into liquid it gives up a portion of this coloring matter. It is soluble and forms a coloring liquid or solution.

The alburnum or sapwood is porous and by forcing this coloring liquid through the pores of the wood, the sap wood is stained corresponding to the color of the heart wood. Heating the liquid sufficiently causes it to circulate more rapidly through the wood, and also causes the wood to give up more of its coloring matter. I discovered that a stain more nearly natural is acquired by a quick rather than a slow process and that by performing the process as rapidly as possible it prevents the coloring matter from deteriorating and the color becomes identical with that of the heart wood. I also discovered that a forced circulation of the coloring liquid in the vessel or container also accelerates the coloring matter through the pores of the wood and that such a process produces a natural coloration without injury to the wood in any commercial sense. By adding a fixing solution the color becomes permanent.

To further explain: Wood contains air and it must be forced out or the wood will be compelled to absorb the coloring matter through the cells of the wood and this requires a longer time than it does when the coloring liquid is forced through the pores. For this reason when the wood is laid longitudinally in the vessel, the coloring liquid attempts to enter both ends of the pores at the same time, thus compressing the air and interfering with the circulation of the coloring liquid through the pores. I discovered that this could be overcome by maintaining a heavier pressure of the coloring liquid at one end of the boards than at the other; and further that by standing the boards on end the pressure at the bottom drives out the air at the top of the board and enables the work of staining to begin much earlier than by other methods. It

shortens the time required to properly stain the wood by producing a more rapid circulation of the coloring solution through the wood. I discovered that when using containers constructed of iron or steel, or in which there were any iron or steel pipes or other members when the coloring solution came into contact with the iron or steel, certain elements in the coloring solution so acted upon the iron or steel that the coloring matter changed from the natural color to a foreign and unnatural color, and I further discovered that vitrified substances did not give up any elements in sufficient quantities to injure the natural color of the coloring matter extracted from the wood or to be commercially injurious to the process of staining; that such substances as wood, wood fibre, and the various compounds manufactured from wood and plant life, concrete, cement, vitrified clay, brick, sand, stone and their compounds, or any vitrified, non-metallic or other substance which does not afford contact between the liquid and any iron or steel, could be used satisfactorily for making the containers without injury to the coloring matter extracted from the wood or injury to the process of staining; and if the container is constructed of iron or steel or their compounds it is advisable to line it with some non-metallic, vitrified or other substance which will prevent the coloring solution from substantially coming in contact with iron or steel.

35 A container, such as I prefer to employ, is shown at 11, and may consist of a body 12, for instance, of iron or steel, provided with an inner lining 13 of a vitrified substance, in which the wood, represented as pieces 14, are placed on end in a body of liquid in the container, the level of which is shown at 24 as covering the wood, the ends of the wood being exposed to the liquid, and the wood retained below the level of the top of the liquid, in suitable manner.

Heart portions of the wood are exemplified at 17, and sap portions of the wood are represented at 18, pores of the wood being represented at 19.

50 The heat for the liquid may be obtained by steam forced into the water, as through the nozzle 20 of an injector 21, which may be of wood. The force of the injected steam will induce circulation of the liquid in the container in the direction of the arrows 22 and induce a flow of the liquid in downward direction toward the injector 20 through a pipe 23, which may also be of wood.

By my improved process woods containing continuous pores and possessing but little coloring matter can be stained or colored in imitation of other woods possessing strong coloring matter, such as poplar with walnut, basswood with butternut, soft maple with cherry, etc.

I attain these objects by my improvement in the process of staining wood which consists of the following: A vessel or container that will hold a liquid should be composed preferably of a non-metallic or vitrified substance such, for example, as wood, wood-fibre, concrete, cement, brick, stone or their compounds, such as vitrified clay, porcelain or any vitrified substance. However, iron or steel should not be used, either in the vessel itself or in any pipes or other members. If the vessel is of an iron or steel substance it should be lined with some non-metallic or other substance excepting iron or steel and no iron or steel substance should be exposed so that the liquid contents will be allowed to act upon it in such a way as to dissolve it. To get the best results it should be constructed so that it will withstand the adequate heating of the liquid contents. The lumber (both the wood to be stained and the wood from which the coloring is to be extracted) is put into the vessel and either stood on end or laid horizontally. If laid horizontally the liquid coloring matter hereinafter referred to should be caused to circulate in such a way as to produce a greater pressure against the lumber at one end than at the other. When stood on end the pressure produced by gravity supplies this requirement. When heat is employed and the wood is arranged with one end higher than the other, gravity is supplemented by the circulation of the liquid subjected to heat. Liquid is placed in the container for the purpose of extracting the coloring matter from the wood. This can be done before or after the wood is placed in the container, but the work is facilitated by adding the liquid after the wood is placed in the container. In order to facilitate the extraction of the coloring matter and to hasten the circulation of the coloring matter through the wood the liquid is subjected to heat and it is maintained in a heated condition until the sap wood has become the same color as the heart wood, or the wood to be stained has taken on the same color as the wood whose color it is sought to imitate. When the coloring or staining process has been completed the coloring liquid may be drawn off and put in another vessel and kept for the next operation. When the second and subsequent operations are started, instead of filling the vessel with water the coloring solution of the previous operation is put in and only enough liquid added to keep the lumber submerged. During the process of staining care should be taken not to prolong the operation unnecessarily because the coloring solution, which I have also referred to as the liquid, has a tendency to deteriorate, and care should also be used not to raise the temperature too high as it becomes injurious to the coloring solution and also the wood.

The time required to properly complete the process of staining runs from two and a half to five days, depending upon the dryness of the lumber, and whether it is forest 5 or field growth. Field growth usually takes longer than forest, and green wood takes longer than seasoned wood. I obtained the best results by using a container made entirely of wood, with no nails or metals of any 10 kind exposed to contact with the coloring fluid; by selecting thoroughly seasoned walnut boards containing part heart wood and part sap wood and placing them vertically in the container; by filling the container with 15 pure water so that the boards were submerged; by heating the water to about 212 degrees Fahrenheit and continuing the process for about three days. I heated the water by forcing steam into the water by means of 20 wooden pipes. This furnished the forced circulation of the coloring solution through the wood.

There are several methods of staining wood but all have certain objections. The method 25 of staining by the usual dipping or by application with a brush is not satisfactory because the heart wood in the same kind of wood varies in color, thus necessitating a great variety of stains to produce the proper 30 color. The stain does not penetrate the wood to any extent and an injury to the board reveals the fact that what was supposed to be heart wood is only an imitation.

The method of steaming is comparatively 35 slow. It usually takes two or three weeks to complete the operation. The coloring matter deteriorates and much of the natural quality is lost or changed, thus producing a dull, unnatural color, rather than the natural, enlivening color effect. It kills the life 40 of the wood; causes it to become brittle or brash and to break easily, and it destroys its usefulness for bending purposes.

Aside from being commercially more 45 economical my process produces none of the objectionable features mentioned. On the contrary, it can be completed in much shorter time. It causes the gradation of color from the heart to the sap wood to be 50 uniform and identical with the heart wood in color. The color has not the appearance of being artificial but has the natural, enlivening color effect. The sap wood in each board takes the same shade of color as the 55 heart wood in the same board, instead of coloring the sap wood of all the boards one color regardless of what may be the shade of the heart wood in each particular board. The stain penetrates the entire board regardless of what may be its thickness so that 60 the shade or color in one part of the board is the same as that in any other part of the board, whether sap or heart wood. It does not kill the life of the wood nor destroy its 65 usefulness for bending purposes nor does it

injure its qualities for polishing or interfere with any of its commercial values or qualities. It is considerably cheaper than other processes.

If desired, suitable coloring matter may 70 be supplied to the liquid in addition to the color constituents extracted from the wood as hereinbefore described.

I claim:

1. The method of treating wood to substantially uniformly color the same, which consists in extracting color constituents from the darker portions of said wood and supplying color constituents so extracted to the lighter portions of said wood by subjecting 75 said wood to the action of a liquid which transforms said color constituents, which liquid is substantially free of contact with iron and with steel.

2. The method of treating wood to substantially uniformly color the same, which consists in extracting color constituents from the darker portions of said wood and supplying color constituents so extracted to the lighter portions of said wood by subjecting 80 said wood to the forced circulation of a liquid which transfers said color constituents, which liquid is substantially free of contact with iron and with steel.

3. The method of staining wood, consisting of placing wood members in a container into which liquid is placed, and constructed so that the liquid contents thereof will not be substantially subjected to contact with any iron and steel, heating the liquid to 100 about 212 degrees Fahrenheit, and causing a forced circulation of the liquid thus heated through the wood to be stained.

4. The method of staining wood, consisting of placing wood members in a container 105 having all parts which are exposed to liquid free from iron and from steel, and containing water, heating the water and causing a forced circulation of the liquid.

5. The method of staining wood, consisting of placing wood members and liquid in a vessel, heating the liquid, causing a circulation of the liquid through the wood, the vessel so constructed as to prevent elements in the liquid from acting chemically upon 110 any iron and any steel used in the construction of the vessel and in heating the liquid.

6. The method of treating wood to substantially uniformly color the same, which consists in extracting color constituents from the darker portions of said wood and supplying color constituents so extracted to the lighter portions of said wood by subjecting 115 said wood to the pressure flow of a liquid which transfers said color constituents, which liquid is substantially free of contact with iron and with steel, and exerting said pressure flow lengthwise of the pores of the wood.

7. The method of treating wood to sub- 120

130

stantially uniformly color the same, which
consists in subjecting wood having different
shades of color to the pressure of a liquid
in the presence of heat, which liquid is sub-
stantially free of contact with iron and with
steel, said pressure exerted lengthwise of the
pores of said wood, whereby to extract color

constituents from the darker portions of said
wood and supply color constituents so ex-
tracted to the lighter portions of said wood, 10
and supplementing said color constituents by
added color.

FREDERICK THOMAS ATKINSON.
